UNITED STATES PATENT OFFICE.

ALFRED W. BRUCE, OF NEW YORK, N. Y., AND JOSEPH B. ENNIS, OF PATERSON, NEW JERSEY.

METHOD OF AND APPARATUS FOR CONTROLLING THE CUT-OFF OF DISTRIBUTION VALVES OF LOCOMOTIVES.

Application filed April 5, 1927. Serial No. 181,100.

Our invention relates to an improved apparatus for controlling the cut-off of distribution valves of locomotives, whereby a substantial economy in the use of steam is effected, and a more efficient operation of the locomotive is ensured.

It is well known in locomotive practice that a late cut-off of the distribution valves, that is, one occurring when the working piston has traversed from 85 to 90% of its stroke, is desirable in starting the locomotive; to provide the maximum power; and that when the locomotive is running, an early cut-off, that is, one occurring when the working piston has traversed from 50 to 65 percent of its stroke, is necessary in order to prevent back pressure. Some locomotives have been equipped with mechanisms which positively limit the movement of the valves to an early cut-off. An objection to such mechanisms is, that when the locomotive comes to a stop, with the crank pins in certain positions, the valves are disposed in positions where steam is entirely cut-off from the cylinders. To remedy this objection, auxiliary ports are provided to admit sufficient steam to start the locomotive. It has been found, however, that such ports soon become clogged with dirt, grease, and other foreign substances, with the result that the efficiency of the locomotive is impaired. Other locomotives have been equipped with valve mechanisms adjustable to late cut-off position for starting, and early cut-off position for running. Such mechanisms usually comprise a reverse lever which can be moved manually to late cut-off position, where it is locked by a latch, which engages with a rack on a quadrant. The return of the lever to early cut-off position is dependent on the judgment of the engineer. Experience has shown that, due to negligence, the reverse lever is frequently left in late cut-off position after the locomotive is started, with the result that a material amount of steam is wasted.

An object of the present invention is to provide a control mechanism for distribution valves, which, in addition to enabling the engineer to move the reverse lever to late cut-off position, to start the locomotive, provides for automatically returning it to early cut-off position, immediately that the engineer releases his pressure thereon.

In the accompanying drawings: Figure 1,

is a side view, in elevation, of a locomotive, 55 having a portion of its cab broken away to show our improved reverse lever mechanism; Fig. 2, a side view, in elevation, and on an enlarged scale, with the lower portion broken away, of our improved reverse lever mechanism, the spring device being shown in vertical section on the line, *a a*, Fig. 4; Fig. 3, a front end view of the mechanism shown in Fig. 2; and Fig. 4, a transverse section, on a further enlarged scale, taken on the line, 65 *b b*, Fig. 2, showing details of the latch.

In the practice of our invention, referring descriptively to the specific embodiment thereof which is herein exemplified as applied in a locomotive of usual type, embodying a Walschaert valve gear, which is diagrammatically shown, and a power reverse gear of usual type, the reverse lever 10, is mounted in the cab, and has an upper arm, which terminates in a handle, and a lower arm, to which is pivotally connected one end of the reach rod, 11. The other end of the reach rod is connected to the power reverse gear, 12. The lever is fulcrumed, intermediate its length, on a pin, 10^a, which is attached 80 to the quadrant support, 13.

A latch handle, 14, is pivoted to the upper arm of the lever, by a pin, 14^a, and to one end of a link, 16, by a pin, 16^a. The other end of the link is pivoted to the latch, 18, which is mounted for vertical movement in a housing, 19. The latch is formed with a vertical slot, 20, through which passes a bolt, 21, and is provided, at its bottom, with a row of teeth, 22, adapted to engage in the notches, 23, of a quadrant, 24, bolted to the support, 13. The upper face of the quadrant is notched for only a portion of its length, an end portion being left smooth for a purpose which will hereinafter be apparent.

The latch is normally urged downward, so that its teeth will engage the notches in the quadrant, by a spring, 26.

In operating the reverse lever to start the locomotive, the engineer grasps both the lever and the latch handle, exerting a squeeze which frees the latch teeth from the notches, and then pushes the lever to late cut-off position, indicated by the line, *c c*, Fig. 2. He then releases the lever, whereupon the latch drops, and as the end of the quadrant is smooth, the lever may be moved back to early cut-off position, indicated by the line, *d d*,

with the latch down, at which point the teeth of the latch will drop into notches in the quadrant, locking the lever.

We have observed that engineers, in starting locomotives, push the reverse lever to late cut-off position, but frequently neglect to return it to early cut-off position when the locomotive is running. This neglect is the source of a material waste of steam and considerably increases the cost of operating the locomotive. In order to prevent this waste, we provide mechanical means for returning the reverse lever to early cut-off position, immediately that the engineer releases the lever. This means comprises a stop, 27, in the form of a flat plate, which extends laterally from and above the quadrant, and is secured to one end thereof by a bolt, 27^a. The reverse lever is forged with a lateral extension, 31, in which is provided a cylindrical pocket. One end of a helical spring, 32, is fitted in the pocket and the other end of the spring projects forwardly of the reverse lever, and is enclosed in a cylindrical casing, 34, adapted to telescope into the pocket, when the spring is compressed. In order to secure the casing, 34, to the spring, and to provide for adjusting the spring to different compression lengths, a bolt, 35, is employed. This bolt has a head, which fits in a recess in the end of the casing, 34, and a shank, which passes through the end of the casing, and the end of the pocket. The end of the bolt projecting beyond the end of the pocket, is threaded and carries two nuts, 36, by which any desired adjustment of the spring may be effected.

The operation of the device is as follows. In starting the locomotive, the engineer grasps the handles of the lever and the latch, and exerting a squeeze, frees the teeth of the latch from the notches in the quadrant, permitting the lever to be pushed to late cut-off position. As the lever is pushed to late cut-off position, the cylindrical casing, 34, will be brought into abutment with the stop, 27, whereupon the casing, 34, will telescope into the pocket, compressing the spring, 32, and permitting the lever to be pushed to late cut-off position. After the locomotive is started the engineer releases the lever, whereupon the latch drops, but as the end portion of the

quadrant beneath the latch is unnotched, the lever is free to be moved back to early cut-off position, by the action of the spring, 32. When the lever reaches early cut-off position, the teeth of the latch engage notches in the quadrant, thereby locking the lever.

One of the obvious modifications of the invention, which is a mechanical equivalent of the form illustrated, is to apply the spring device to the quadrant and the stop to the lever.

The present invention provides a reverse lever mechanism enabling the reverse lever to be pushed to full cut-off position to start the locomotive, but which will return the lever automatically to early cut-off position, irrespective of draw bar pull, immediately that manual pressure on the lever is released, thus ensuring the proper cut-off of the valves for starting and running conditions, and obviating any chance of waste of steam by reason of the negligence of the engineer. The improvement effects a substantial economy in operating costs.

It is to be noted that for a switching engine, both ends of the quadrant should be made unnotched, to permit the lever to be thrown to late cut-off position, for either ahead or reverse, and a suitable spring or springs, and stops provided to effect the automatic return of the lever to early cut-off position from either end of the quadrant.

We claim as our invention and desire to secure by Letters Patent:

Distributing valve operating mechanisms, comprising, in combination with the reach rod and the hand lever operatively connected thereto, of a quadrant over which said lever plays, notches in the centre portion only of said quadrant, a latch carried by said lever to engage said notches, a handle for lifting said latch out of such engagement, a stop secured to one end of said quadrant, a socket carried by said lever adjacent the quadrant, a hollow piston slidable in said socket, a spring between the socket and piston ends, and means to limit the outward movement of said piston by said spring.
